PINHOLE GRINDING OR HONING TOOL

Filed Feb. 17, 1932

UNITED STATES PATENT OFFICE

WILLIAM PAUL ROBERTS, OF GREENSBURG, INDIANA

PINHOLE GRINDING OR HONING TOOL

Application filed February 17, 1932. Serial No. 593,608.

My invention relates to tools for grinding and polishing the walls of piston pin-holes, bearing bushings and other small diameter apertures in cast iron, steel, aluminum, 5 bronze or alloy metals.

Heretofore tools have been provided for the purpose but their use has been limited to a narrow range of adjustments requiring several tools to make up a set to fit the 10 entire range of pin holes from the minimum to the maximum met with in a given work. For example, there has come upon the market a piston pin hole grinder which is sold in sets of three, one of which has a range of 15 adjustment .730" to .870", another from .860" to .995", and the third from .990" to 1.135". Another set is on the market which is made up of four tools to cover a given range of from .730" to 1.130", and four more 20 for truck sizes ranging in adjustment from 1.130" to 1.530". My invention has for one of its objects to provide an improved honing tool of such design and construction that one tool will cover the whole range of sizes 25 now covered by the sets of three or four tools, thus reducing the number of tools which the mechanic must have in his shop in order to render satisfactory service to his customers and also reducing the invested 30 expense greatly.

A further object is to provide a hone by the use of which the pin holes can be honed from standard to the next oversize in but a few seconds, thereby greatly decreasing the 35 time-labor charge on a given job.

Further, it is an object to provide a pin hole grinder which may be used on spring bushings, shackle and axle bushings, either 40 straight or tapered.

Further, it is an object to provide a tool embodying the advantageous characteristics above alluded to, which, when once adjusted to the work, will be locked, i. e. will positively hold the adjusted relation of its parts 45 against slipping or loosening up while in use.

Further, it is an object to provide a tool such as above indicated so designed that it 50 may be adjusted while in position in the hole.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying 55 drawing, in which:

Figure 1 is a perspective view of the tool in use, a piston being shown in sectional perspective.

Figure 2 is an elevation of the tool, one of 60 the abrading elements being shown in vertical section.

Figure 3 is an enlarged detail vertical longitudinal section of one end of the tool.

Figure 4 is a cross section on the line 4—4 70 of Figure 3.

Figure 5 is a detail perspective view of one of the emery cloth abrasive elements.

Figure 6 is a detail perspective view of one of the stone abrasive elements. 75

Figure 7 is a longitudinal section showing how the tool may be adjusted for tapered holes.

In the drawing in which like numerals of reference indicate like parts in all of the 80 figures, 1 represents a mandrel having flattened portions 2 and 3 spaced a suitable distance, the mandrel having threaded portions 4 and 5 beyond the flattened portions 2 and 3.

6 is the end of the mandrel which is insertible in the chuck of the driving engine. The driving engine may be any suitable one for the purpose as for instance a handle operated or a power operated drill drive. The flattened portion 2 which is adjacent the end 85 of the mandrel that is remote from the end 6 has a longitudinal slot 7 through which one of the link pivot pins 8 passes. The other link pivot pin 9 passes through a round hole in the flattened portion 3. 90

The mandrel 1 is longitudinally bored as at 9 to provide a concavity for the adjusting screw pin 11, the bore being threaded as at 10 to cooperate with the threaded portion 13 of the adjusting screw pin 11. The adjusting 100

screw pin 11 has an annular groove 12 to receive the link pivot pin 8 that passes through the slot 7. By placing a screw driver in the kerf 14 of the adjusting screw pin 11 it may be turned to advance or retract it and thereby move the adjacent link pivot pin back and forth along the slot 7 to increase or diminish the distance between the two pivot pins 8 accordingly for a purpose hereinafter more clearly understood.

15 is the abrasive element spreader abutment which may be a knurled disk or a nut, and 16 designates a correspondingly formed abrasive element contracting abutment, the 15 abutments 15 and 16 being threaded on the threaded portions 5 and 4 respectively.

17 designates the abrasive element carrier bars of which there are two. These bars are of curved cross section approximately to 20 conform to the curvature of the mandrel so that when they are in the contracted position they will lie in proximity to the mandrel. The longitudinal edges 18 of the bars 25 17 are somewhat reduced in thickness to fit the U-shaped attaching strips 23 which carry the abrasive elements 22. The bars 17 have suitable slots 19 into which the links 21 project, there being link pins 20 provided for pivotally connecting the links 21 to the bars 30 17.

The metal edge strips 23 are bent back upon themselves as at 24 to form a channel in which the edges of the abrasive element (emery cloth) is held by punchings 25 or 35 other suitable means so that when the strips 23 are in engagement with the edges 18 the abrasive element 22 will be tightly fitted to the outer curvatures of the abrasive carrier bars 17.

40 While an emery cloth abrasive may be used on each carrier bar I preferably provide one of the carrier bars with a stone abrasive element 30 mounted on a rigid backing 28 of metal having its ends turned under to form 45 grooves 29 to fit the edges 18 of the bars 17.

26 and 27 designate recesses in the flattened portions of the mandrel 1 to receive the pivot pins 20 when the bars 17 are in the contracted position.

50 When the adjusting screw pin 11 is so positioned that the distance between the centers of the pin 8-8 and the distance between the pins 20-20 are equal, then any movement of the links will impart parallel motion to the carrier bars 17 towards and from the mandrel, the motion, of course, being a swinging motion through the medium of the links 21.

When it is desired to use the tapered holes 60 the distance between the centers of the pins 8-8 is varied accordingly by turning the adjusting screw 11 to increase or diminish that distance as may be desired. When the distance is increased the bars 17 will incline toward the end having the adjusting screw pin

11, whereas when the distance is decreased the inclination will be in the other direction.

In using my invention the abutment 16 is unscrewed and with the bars 17 in the contracted position the tool is placed in the hole 70 to be honed. After the tool has been placed in the hole to be honed the abutment member 15 is screwed up to expand the bars 17 from the mandrel 1 and cause them to engage the wall of the hole, after which the abutment 16 is replaced and screwed up tight. The tool is then ready to be chucked into the driving engine and placed under rotation. If it is desired to expand the tool further in order to abrade deeper, the abutment 16 is slackened and the abutment 15 tightened correspondingly.

If the hole is a tapered hole, as for instance the holes in wheel hubs for the axle ends, the 85 adjusting pin 11 is turned to permit the required inclination of the bars 17 which are expanded into contact with the wall of the hole by tightening the abutment 15. The adjustment can then be made secure by tightening the abutment 16 against the adjacent ends of the bars 17.

90 From practical tests I find that I can cut the pin holes in the pistons of internal combustion engines from standard to .010" in thirty seconds. This accomplishment has not been found possible by any of the tools now 95 on the market and known to me.

From the foregoing description, taken in connection with the accompanying drawing, it is thought the construction, operation and 100 many advantages of my invention over the tools of the prior art will be clear to those skilled in the art to which the invention appertains.

What I claim is:

1. A hone of the character stated comprising a mandrel having threaded portions spaced apart, a threaded abutment member on each of said threaded portions, abrasive carrier bars, sets of links and pivot pins for mounting said carrier bars on said mandrel, 105 said threaded abutments arranged to abut the ends of said bars and adjust and secure said bars in their adjusted positions, and abrasives carried by said bars.

2. A hone of the character stated comprising a mandrel having threaded portions spaced apart, threaded abutment members on said threaded portions, abrasive carrier bars, sets of links and pivot pins for mounting said carrier bars on said mandrel, said threaded abutments arranged to abut the ends of said bars and adjust and secure said bars in their 110 adjusted positions, and abrasives carried by said bars, said abrasives including abrasive sustaining backs overlying said bars with their longitudinal edges anchored to the longitudinal edges of said carrier bars.

3. A hone of the character stated comprising a mandrel having threaded portions spaced apart, a threaded abutment member 115

on each of said threaded portions, abrasive carrier bars, sets of links and pivot pins for mounting said carrier bars on said mandrel, said threaded abutments arranged to abut the ends of said bars and adjust and secure said bars in their adjusted positions, and abrasives carried by said bars, the distance between the pivot pins connecting the links to the carrier bars being equal to one another 10 and to the distance between the pivot pins connecting the links to the mandrel.

4. A hone of the character stated comprising a mandrel having threaded portions spaced apart, threaded abutment members 15 on said threaded portions, abrasive carrier bars, sets of links and pivot pins for mounting said carrier bars on said mandrel, said threaded abutments arranged to abut the ends of said bars and adjust and secure said bars 20 in their adjusted positions, and abrasives carried by said bars, said abrasives including abrasive sustaining backs overlying said bars with their longitudinal edges anchored to the longitudinal edges of said carrier bars, the 25 distance between the pivot pins connecting the links to the carrier bars being equal to one another and to the distance between the pivot pins connecting the links to the mandrel.

30 5. A hone of the character stated comprising a mandrel having threaded portions spaced apart, threaded abutment members on said threaded portions, abrasive carrier bars, sets of links and pivot pins for mounting 35 said carrier bars on said mandrel, said threaded abutments arranged to abut the ends of said bars and adjust and secure said bars in their adjusted positions, and abrasives carried by said bars, said abrasives including 40 abrasive sustaining backs overlying said bars with their longitudinal edges anchored to the longitudinal edges of said carrier bars, the distance between the pivot pins connecting the links to the carrier bars being equal to one 45 another and to the distance between the pivot pins connecting the links to the mandrel, the pivot pins connecting the links to the carrier bars being fixed as to their relative positions, at least one of the pivot pins connecting the 50 links to the mandrel being adjustable toward and from the other to vary the distance between the same, and means to hold said adjustable pin when once adjusted against accidental displacement.

55 6. A hone of the character stated comprising a mandrel having threaded portions spaced apart, a threaded abutment member on each of said threaded portions, abrasive carrier bars, sets of links and pivot pins for 60 mounting said carrier bars on said mandrel, said threaded abutments arranged to abut the ends of said bars and adjust and secure said bars in their adjusted positions, and abrasives carried by said bars, the distance between 65 the pivot pins connecting the links to the

carrier bars being equal to one another and to the distance between the pivot pins connecting the links to the mandrel, the pivot pins connecting the links to the carrier bars being fixed as to their relative positions, at least one of the pivot pins connecting the links to the mandrel being adjustable toward and from the other to vary the distance between the same, and means to hold said adjustable pin when once adjusted against accidental displacement. 70

7. A hone of the character stated comprising a mandrel having threaded portions spaced apart, threaded abutment members 80 on said threaded portions, abrasive carrier bars, sets of links and pivot pins for mounting said carrier bars on said mandrel, said threaded abutments arranged to abut the ends of said bars and adjust and secure said bars in their adjusted positions, and abrasives including abrasive sustaining backs overlying said bars with their longitudinal edges of 85 said carrier bars, the distance between the pivot pins connecting the links to the carrier bars being equal to one another and to the distance between the pivot pins connecting the links to the mandrel, the pivot pins connecting the links to the carrier bars being fixed as to their relative positions, at least one of the pivot pins connecting the links to the mandrel being adjustable toward and from the other to vary the distance 90 between the same, and means to hold said adjustable pin when once adjusted against accidental displacement. 95

8. A hone of the character stated comprising a mandrel having threaded portions spaced apart, a threaded abutment member 105 on each of said threaded portions, abrasive carrier bars, sets of links and pivot pins for mounting said carrier bars on said mandrel, said threaded abutments arranged to abut the ends of said bars and adjust and secure said bars in their adjusted positions, and abrasives carried by said bars, the distance between the pivot pins connecting the links to the carrier bars being equal to one another and to the distance between the pivot pins connecting the links to the mandrel, the pivot pins connecting the links to the carrier bars being fixed as to position, at least one of the pivot pins connecting the links to the mandrel being adjustable toward 110 and from the other to vary the distance between the same, and means to hold said adjustable pin when once adjusted against accidental displacement. 115

9. A hone of the character stated comprising a mandrel having threaded portions spaced apart, threaded abutment members 125 on said threaded portions, abrasive carrier bars, sets of links and pivot pins for mounting said carrier bars on said mandrel, said 130

threaded abutments arranged to abut the ends of said bars and adjust and secure said bars in their adjusted positions, and abrasives carried by said bars, said abrasives including abrasive sustaining backs overlying said bars with their longitudinal edges anchored to the longitudinal edges of said carrier bars, the distance between the pivot pins connecting the links to the carrier bars being equal to one another and to the distance between the pivot pins connecting the links to the mandrel, the pivot pins connecting the links to the carrier bars being fixed as to their relative positions, at least one of the pivot pins connecting the links to the mandrel being adjustable toward and from the other to vary the distance between the same, and means for moving said adjustable pin throughout its range of adjustment and holding said adjustable pin in its adjusted positions.

10. A hone of the character stated comprising a mandrel having threaded portions spaced apart, a threaded abutment member on each of said threaded portions, abrasive carrier bars, sets of links and pivot pins for mounting said carrier bars on said mandrel, said threaded abutments arranged to abut the ends of said bars and adjust and secure said bars in their adjusted positions, and abrasives carried by said bars, the distance between the pivot pins connecting the links to the carrier bars being equal to one another and to the distance between the pivot pins connecting the links to the mandrel, the pivot pins connecting the links to the carrier bars being fixed as to their relative positions, at least one of the pivot pins connecting the links to the mandrel being adjustable toward and from the other to vary the distance between the same, and means for moving said adjustable pin throughout its range of adjustment and holding said adjustable pin in its adjusted positions.

11. A hone of the character stated comprising a mandrel having threaded portions spaced apart, threaded abutment members on said threaded portions, abrasive carrier bars, sets of links and pivot pins for mounting said carrier bars on said mandrel, said threaded abutments arranged to abut the ends of said bars and adjust and secure said bars in their adjusted positions, and abrasives carried by said bars, said abrasives including abrasive sustaining backs overlying said bars with their longitudinal edges anchored to the longitudinal edges of said carrier bars, the distance between the pivot pins connecting the links to the carrier bars being equal to one another and to the distance between the pivot pins connecting the links to the mandrel, the pivot pins connecting the links to the carrier bars being fixed as to their relative positions, at least one of the pivot pins connecting the links to the mandrel be-

ing adjustable toward and from the other to vary the distance between the same, and means for moving said adjustable pin throughout its range of adjustment, said moving means comprising a rotatable pin threaded into a socket in said mandrel and having a groove to receive said adjustable pin, said mandrel having an elongated slot for said adjustable pin.

12. A hone of the character stated comprising a mandrel having threaded portions spaced apart, threaded abutment members on said threaded portions, abrasive carrier bars, sets of links for connecting the respective carrier bars directly to said mandrel, pivot pins connecting said links to the respective carrier bars, pivot pins passing through apertures in said mandrel to each of which a pair of links is pivoted, said threaded abutments arranged to abut the respective ends of said bars and adjust and secure said bars in their adjusted positions, and abrasives carried by said bars.

13. A hone of the character stated comprising a mandrel having threaded portions spaced apart, threaded abutment members on said threaded portions, abrasive carrier bars, sets of links for connecting the respective carrier bars directly to said mandrel, pivot pins connecting said links to the respective carrier bars, pivot pins passing through apertures in said mandrel to each of which a pair of links is pivoted, said threaded abutments arranged to abut the respective ends of said bars and adjust and secure said bars in their adjusted positions, and abrasives carried by said bars, one of the pivot pins connecting a pair of links to the mandrel having movement in the direction of the axis of the mandrel and means carried by the mandrel for effecting such movement for the purposes described.
